United States Patent Office

Des. 196,802
Patented Nov. 5, 1963

196,802

MOWER HOUSING

Donald E. Dailey, Vanderburgh County, Ind., assignor to
Hahn, Inc., Evansville, Ind., a corporation of Indiana

Filed Mar. 28, 1963, Ser. No. 74,169

Term of patent 14 years

(Cl. D40—1)

Fig. 3

Fig. 2.

Fig. 1.

Fig. 4.

FIG. 1 is a perspective view of a mower housing showing my new design; the dotted lines showing the mower are disclosed for illustrative purposes only.

FIG. 2 is a top plan view of the instant mower housing;

FIG. 3 is a view in side elevation of the instant ornamental design for mower housing, looking from left to right in FIG. 2; and,

FIG. 4 is a view in rear elevation of the instant mower housing.

I claim:

The ornamental design for a mower housing, as shown and described.
